SIGN HOLDER HAVING RECESSED ROTATABLE SIDE MEMBERS

John Heyward Stokes, Atlanta, Ga.

Application December 19, 1944, Serial No. 568,829

3 Claims. (Cl. 40—125)

1

Generically this invention relates to sign supporting mediums or holders, but it more especially is directed to such a holder adapted for both outdoor and indoor advertising display purposes.

One of the principal objects of this invention is the provision of an advertising display supporting frame or holder, in which is insertable and removable a cardboard or other panel of display indicia, and means operable to secure and release said panel with respect to said frame.

Another important object of this invention is the provision of a supporting frame or holder having its side members recessed to engage the side edges of an advertising display bearing or supporting cardboard or other panel material, and means carried by said frame adapted to engage the ends of said panel and movable to panel locking and releasing positions to secure the display surface in the frame without the use of nails, tacks, paste, glue, or the like.

A still further object of this invention is the provision of a billboard frame or holder having means extending longitudinally of its side members adapted to retainingly engage the side edges of an advertising display panel element or plurality of superimposed elements mounted intermediate said side members, and brace means interconnecting said side members adjacent each end of said panel elements, said brace means being rotatable to normal retaining engagement with the end of the exposed panel to retain the panels in the frame, and in the reverse direction to release the same, whereby the respective panels may be successively removed to expose to view the display matter of the underlying panel.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a front elevation of my improved sign holder or frame device.

Fig. 2 is a vertical section taken on the line 2—2 of Fig. 1.

Fig. 3 is an enlarged section on the line 3—3 of Fig. 1.

Fig. 4 is a side elevation of one of the side bars on the line 4—4 of Fig. 1.

Fig. 5 is a similar view to Fig. 3 with the display or sign medium removed.

2

Fig. 6 is a perspective view of one of the locking or sign retaining members.

Bill-board and other advertising display frames and holders heretofore employed, especially for outdoor use, have presented many disadvantages, such as, being expensive to construct, necessitating applying a coating of paste and the like to the surface of the frame or holder and/or to the back of the display medium, or by nailing, tacking, or otherwise securing the display surface against displacement by the elements. Further, the display is frequently changed, and each time this procedure must be repeated, and often the old surface must be first torn off leaving a ragged or uneven base, and it was to overcome such disadvantages by providing a novel supporting and holding frame adapted to contain one or a plurality of display panel elements, and means instantly operable to panel or sign element securing or removing positions, thereby permitting their ready installation or removal, that I designed the device forming the subject matter of this invention.

In the illustrated embodiment characterizing this invention there is shown an advertising display or sign holder comprising a rectangular frame (A) formed with parallel side bars or members 1, in the present instance, with the opposite front corners rounded off as at 2 and adjacent thereto formed with a pair of spaced openings 3 and 4, respectively. Mounted in the opposite openings 3 of the respective side bars 1 are the cross bars or end members 5 of a length slightly greater than the width of the frame and which are firmly secured to the side bars by nails or other fastening means 6, or in any well known manner. A sign bearing medium 7 of cardboard or other suitable material is adapted to be inserted in said frame, and rotatably mounted in the horizontally opposite openings 4 spaced from end bars 5 at each end of the frame are the rotatable locking and releasable members 8 adapted for releasable engagement with the ends of the sign or display medium 7, as will directly more fully appear. The members 8 are retained in said openings and against endwise movement by the end blocks 9 also mounted in said openings 4 and fixedly retained by nails 6 or other suitable means. Each of said locking members 8 is formed with a segmental cut out portion 10 extending throughout its length, and, in the present instance, the walls of which are at substantial obtuse angles to each other.

The inner side surfaces of side bars 1 are formed with longitudinal grooves or recesses 11

intersecting at each end the openings 4 at points off center and nearer their rear edges. This construction including and in conjunction with the locking bars 8 permits the use of a plurality of superimposed display elements or sheets 7, or a heavier single element, and their insertion in or removal from the frame as desired, and in order that this may be facilitated in connection with the heavier stock, the outer edges of said recesses 11 may be slightly beveled or rounded as at 12.

Interconnecting the side bars 1 spaced inwardly from members 8 are the brace members 13 flush with the bottom wall of grooves 11 so that in addition to strengthening the frame they constitute a bed or support for the cardboard or other advertising display panels or sheets carrying the advertising indicia or other display matter 14.

The sign holder or frame (A) may be constructed of any suitable material and of any size, hung by bracket members 15 from either the side or end, placed on a suitable support or otherwise mounted for outside or inside use, depending upon the exigencies of the particular requirements. Where the display panel is of cardboard or other substantially stiff material no backing member is necessary, and such cardboard could also serve as a backing where it is desired to use a thin display sheet or number of superimposed sheets to be successively removed, following a predetermined display period, or, a suitable backing panel or board may be used and/or permanently attached to the frame if desired.

The display members or panels 7 are of a width so that when flattened out the side edges extend within the recesses 11 and of a length so that their ends will extend to substantially the center of openings 4 and within the segmental cut out portions 10.

To place in or load the holder or device with one or more of the display elements, it is only necessary to rotate the end members 8 to position the cut out portions 10 facing each other and sufficiently open to receive the ends of the panels, then spring the display panel slightly to engage its or their side edges in the recesses 11 and then rotate members 8 to bring their upper edges or walls into binding or locking engagement with the exposed surface of the display panel to securely fasten or lock said panel or panels in the frame. To remove the panels or a panel it is necessary to forcibly actuate said members 8 to their initial open positions.

From the above description it is apparent that I have designed a sign-board or holder for advertising or other display indicia, posters, and the like, especially applicable to outdoor use but also adapted for indoor display purposes as well; one manufacturable at a negligible cost, pleasing in appearance, versatile in its adaptive use, and efficient for the purposes intended.

Although in practice it has been found that the form of the invention illustrated in the accompanying drawings and referred to in the above description as the preferred embodiment is the most efficient and practical, yet realizing that

conditions concurrent with the adoption of the device will necessarily vary, it is desired to emphasize that various minor changes in details of construction, proportion and arrangement of parts, may be resorted to within the scope of the appended claims without departing from or sacrificing any of the principles of this invention.

Having thus described the invention, what is desired protected by Letters Patent is as set forth in the following claims:

1. A magazine poster display device comprising a retaining frame defining an opening, said frame being formed within said opening with a seat adapted to receive a plurality of posters, and locking elements at opposite edges of the magazine and within the frame for engaging the opposite free edges of the outermost poster within the magazine, said locking elements being channeled to provide a poster engaging surface and partially rotatable to position said surface into locking and unlocking engagement with the exposed surface of the outermost poster whereby to lock said posters in said seat and to permit their removal therefrom.
2. A poster display device comprising a retaining frame defined by parallel side members, means interconnecting said side members and forming within said frame a poster receiving seat, said members being formed with means adapted to receivingly engage opposite edges of a poster when in position in said seat, and roller locking elements carried by said side members and situated at the opposite ends of said seat, said roller elements being formed to provide poster engaging surfaces and partially rotatable to position said surfaces into locking and releasing engagement with the exposed poster surface whereby to lock said poster in said seat and permit its removal therefrom.
3. A poster display device comprising a retaining frame defined by parallel members, means interconnecting said parallel members and forming within said frame a seat adapted to receive a plurality of posters, and roller locking elements carried by said members and located at opposite edges of said seat, said roller elements being formed to provide means having poster engaging and releasing positions and partially rotatable to position said means into locking and releasing engagement with the exposed surface of the outermost poster, and successively with each of the remaining posters upon release and removal of an outermost poster.
